J. F. MANDERNACK

SANDING DEVICE FOR AUTOMOBILES

Filed Feb. 7, 1925

Patented Oct. 26, 1926.

1,604,705

UNITED STATES PATENT OFFICE.

JOHN F. MANDERNACK, OF CHICAGO, ILLINOIS.

SANDING DEVICE FOR AUTOMOBILES.

Application filed February 7, 1925. Serial No. 7,456.

This invention relates to a sanding device for vehicles adapted to apply sand in front of the braking wheels of the vehicle.

It is an object of this invention to provide an automatic sand applying apparatus for vehicles wherein the sanding mechanism is operated only when the brakes are applied and is rendered totally inoperative at the will of the driver.

10 It is a further object of this invention to provide an automatically operating sander of the class described wherein the sanding operation can be manually controlled in addition to the automatic control as in cases 15 where additional tractive effort is required or as preventive of skidding under slippery road conditions.

15 It is still another object of this invention to provide a sanding device of the class described automatically operable by either or both the regular or emergency brakes.

20 Other and further important objects of this invention will be apparent from the disclosures in the specification and the accompanying drawings.

25 This invention (in a preferred form) is illustrated in the drawings and hereinafter more fully described.

30 On the drawings:

Figure 1 is a plan view of a vehicle chassis to which a device embodying features of this invention has been applied.

35 Figure 2 is an enlarged detail elevation of the device.

Figure 3 is an enlarged section on the line III—III of Figure 1.

Figure 4 is an enlarged fragmentary view of one of the sand valves.

40 Figure 5 is a detail of the manual control for operating the sanding device.

Figure 6 is a section on the line VI—VI of Figure 2.

As shown on the drawings:

45 An automobile chassis is shown in the drawings, wherein the frame 10 is indicated, as well as the front axle 11, rear axle 12, wheels 13, brake mechanism 14 on the rear wheels, and the intermediate brake-shaft 15 crosswise of the chassis frame. The brakes are operated by the hand lever 16 and brake rod 17 for the emergency brakes and the

50 pedal 18 and brake rod 19 for the foot brakes, both rods actuating levers on component parts of the brake-shaft 15 as is standard practice.

The exigencies of the chassis layout usually require that the emergency and foot brake rods, while parallel, are at different levels, so that in the installation of the device of this invention it is necessary to use an L-shaped bar 20, as shown in Figure 6, spanning the two rods 17 and 19 to form the actuating member for the sanding apparatus. The mounting of the bar 20 on the rods 17 and 19 is such that in pulling either rod to actuate its brake, one end of the bar 20 will be moved to the front of the chassis about the other end as a pivot. If both brakes are applied at the same time 70 the center of the bar will be advanced correspondingly farther, resulting in a greater application of sand, as will be described hereinafter.

75 Sand receptacles 21 are mounted in any suitable way on the chassis adjacent the braking wheels and have outlet pipes 22 normally closed by flap valves 23. Rods 24 extend from these valves to levers 25 on an operating shaft 26 mounted transversely of 80 the vehicle and as shown in Figure 2 supported by the running boards 27 which may also carry the sand receptacles 21. A central lever 28 on the shaft 26 carries a rod 29 with a hook 30 adapted to engage over the 85 bar 20 on the brake rods. Applying either brake moves the bar 20 and thereby acts through the rod 29, shaft 26 and rods 24 to open the sand valves 23.

90 In order to provide for a manual control of the sanding apparatus when it is desired to apply sand independently of the brakes to improve the traction or to prevent skidding, a dash pull control is provided, consisting of a knob 31 and cord 32 trained 95 over suitable pulleys 33 to engage a crank 34 on the shaft 26.

100 In order to prevent the automatic operation of the sanding device under favorable road conditions, means are provided to lift the rod 29 off the bar 20, as shown by dotted lines in Figure 2. This comprises a bell crank member 35 linked to the rod 29 at 36 and having a plunger 37 arranged conveniently for the operation by the driver. When 105 this plunger is pressed downwardly until the notch 38 therein engages the edge of the aperture 39 in the floor boards to retain the plunger against the force of the spring 40. To release the plunger only requires a slight 110 forward movement such as a kick by the operator. To insure positive retention of

the plunger a curled spring 41 is mounted partly in the aperture 49 to press the plunger rearwardly.

I am aware that many changes may be made, and numerous details of construction may be varied through a wide range without departing from the principles of this invention, and I therefore do not purpose limiting the patent granted hereon, otherwise than necessitated by the prior art.

I claim:

In combination with a vehicle and the brake actuating mechanism thereof, a bar

bridging the hand and foot brake pull rods and adapted to be moved by the actuation of either brake rod, sand discharging mechanism carried by the vehicle, a hooked member associated with the discharging mechanism and adapted in one position to engage said bar, and manually controlled means for disengaging said hooked member from said bar.

In testimony whereof I have hereunto subscribed by name.

JOHN F. MANDERNACK.
